UNITED STATES PATENT OFFICE.

CHARLES EWEN CAMERON, JR., OF EAST ORANGE, NEW JERSEY.

PIANO ACTION.

Application filed April 26, 1923. Serial No. 634,699.

The invention relates in general to an improved form of piano action and specifically relates to certain details of construction in the mechanism for striking one of the piano strings by the actuation of its associated "key".

In the following specification and in the claims the term "key" will be used to designate either the manually actuated key, commonly found in hand played instruments, or to designate any other abstract moving parts, such as the pneumatics commonly found in player pianos.

More minutely defined the invention relates not only to the action considered as a whole but also to certain details thereof, such for instance, as an improved form of key actuated abstract; an improved form of hammer and its associated mechanism located between the abstract and the string, and to a novel arrangement of soft pedal construction for modifying the sound from one or more strings of the instrument.

Piano actions of the type herein disclosed include rather complicated mechanism between the abstract and the string striking hammer. These known actions include certain wippens, jacks, links, and springs, together with numerous pivotal connections, each one of which contributes an increment of frictional resistance and which collectively require the expenditure of a material amount of actuating force to effect a playing operation of the device. Further, in known forms of actions a part of the manual or mechanical force expended on any one of the keys is required to positively do work in dampening out the vibration of the hammer in its recoil from the string. All these factors act to render the old form of action extremely inefficient and efficiency is necessary especially in mechanically played instruments.

Aside from this lack of economy in utilization of force expended, the multiplicity of separate parts increased the number of possible parts which may become worn or damaged and as a result such constructions are quite liable to become damaged, and can be repaired only by the skilled workmen and are not susceptible of being repaired at home by the unskilled usual user.

The primary object of the invention is to simplify the present form of piano action while retaining all of the advantages of the present type.

Incidental to this general desideratum the invention has for other objects the reducing of the number of parts between the abstract and the hammer to a single element so as to minimize points of possible frictional resistance and in general to provide a form of action in which the actuating force employed on a key is economically utilized almost entirely to effect a movement of the hammer in its string striking movement. Further featuring simplicity in construction another object of the invention is to provide a piano action in which the usual multiplicity of adjustments have been reduced to a single, easily manipulated regulation and in the present disclosure this regulation is confined to the readily accessible abstract of the action.

Another object of the invention is to provide in connection with the hammer a construction which will minimize any tendency towards blocking and in which the tendency of the hammer to vibrate on its recoil is damped out by frictional resistance which does not interfere with the succeeding actuation of the hammer and which contributes to the object of efficiency in operation by not utilizing any of the energy of the hammer actuating mechanism for the purpose of maintaining the hammer in its normal inoperative position.

Still another object of the invention is to provide a piano action in which the parts can be readily demounted for repair and substitution and in which certain wearable or readily damaged parts can be organized as parts of replaceable units. It is understood that such replacement units may be supplied by the piano manufacturer and easily substituted for worn or damaged units by the household user and without necessity of employing skilled labor or using any tools other than a screw-driver.

In connection with the feature of any easy adjustment, another object of the invention is to provide in connection with the hammer a bendable wire shank which permits an easy locating of the hammer head relative to its associated string and which adjustment may be effected after the mechanism is installed in place and without necessity of adjusting any other part of the action to effect the requisite hammer head adjustment.

Another object of the invention is to provide an improved form of soft pedal mechanism which features a modification of the

energy inherent in the blow striking the strings by varying the distance of the hammer throw while maintaining the mass action of the hammer actuating mechanism.

5 Various other objects and advantages of the invention will be in part obvious from an inspection of the accompanying drawings and in part will be more fully set forth in the following particular description of one 10 form of mechanism embodying my invention, and the invention also consists in certain new and novel features of construction and combination of parts hereinafter set forth and claimed.

15 In the accompanying drawings:—

Figure 1 is a view in side elevation and partially in section of a piano action constituting a preferred embodiment of the invention and which is intended to represent one 20 of a set of such actions usually installed in the piano in sets of five or six;

Figure 2 is a vertical sectional view taken centrally through the carriage shown in elevation in Fig. 1; and

25 Figures 3 and 4 are each transverse sectional views taken respectively on the lines 3—3 and 4—4 of Fig. 1.

In the following description and in the 30 claims, parts will be identified by specific names for convenience of expression but they are intended to be as generic in their application to similar parts as the art will permit.

In the drawings there is shown certain 35 supports 10 constituting fixed parts of the piano casing, together with a key-board 11 on which is positioned one of the keys 12 of the manually actuated type, together with its associated string 13.

Resting on and supported entirely by the 40 key 12 is an abstract 14. This abstract is in the form of a straight rod, guided for vertical movement in a pair of apertures 15 and 16 extending through vertically spaced parts 17 and 18 of the support 10. It is a 45 feature of this construction to minimize frictional resistance to the movement of the abstract and preferably the parts of the abstract which extends through the apertures are formed of thin wire and the apertures are outlined by felt sleeves 19 designed to constitute anti-friction guideways. Opposite ends of the abstract are defined by rounded heads 20 and 21 of which the lower 50 head bears on the key and is entirely supported thereby. The top of the upper head 20 provides a rounded bearing surface 22 for supporting and limiting the recoil movement of a hammer actuating mechanism hereinafter more fully described.

55 For the purpose of varying the operative length of the abstract and in this way adjust the normal inoperative position of the hammer actuating mechanism, the abstract is formed of a plurality of parts in screw 60 threaded engagement to permit axial adjust-

ment. In the form illustrated the abstract includes a body portion 23 into one end of which is threaded one end of one of the wires 24, constituting the connections between the heads and the body portion of the abstract. Smooth portions 25 of these wires move through the felt lined apertures 15 and 16. This variable length abstract constitutes all of the necessary regulation for the action and as this abstract is readily accessible through the bottom front of the piano casing the necessary regulation is thus confined to a single readily accessible place in the piano.

65 A support 26 herein shown to be a pair of spaced uprights is mounted on the support 10 and is secured in removable position by means of a pair of screws 27 and 28. It is herein suggested that a pair of these supports be assembled as a readily removable unit and in either case this support will be identified hereinafter as a block. In some cases where there is available room there may be used one block and associated mechanism for each string and abstract but in practice it is preferable to assemble the hammer actuating mechanisms in sets of four or five as suggested in the showing in Figure 3 and to tie the sets together. This is attained by the use of some suitable form of fastening means which will permit the replacement at will of any one set or of any one block and its associated mechanism without disturbing the other sets in the piano or the other blocks in the set.

70 Referring to the single block as explanatory of any block in the set there is shown a pivot pin seat 28' in which is mounted a pivot pin 29 and which pivot pin will have a length sufficient to constitute the pivot pin of all of the blocks in a set, as shown in Figure 3. The pivot pin is secured in position by means of a pair of finger pieces 30, each in turn held in place by one 75 of the screws 28. The pivot wire extends beyond opposite ends of each set and one such projecting portion of the wire of an adjacent set is shown at 31 secured in place by the finger 30 of an end block. It is, of course, within the scope of this disclosure to provide a separate pivot pin for each block.

75 Pivotedly mounted in each block and removable bodily therewith is a carriage or hammer actuator 32 in the form of a lever which extends horizontally and rests on the bearing surface 22 of its associated abstract. The carriage is weighted so that normally it rests on the abstract but is otherwise free of the abstract so that the abstract may fall away from the carriage without carrying the carriage with it. The carriage is limited in its hammer actuating movement, under the lifting effect of the 80

abstract, by engaging the underside of an overhanging stop 33 constituting a fixed part of the piano casing.

The carriage is provided on the side of its fulcrum adjacent the abstract with an upstanding post 34 having a head 35. The edge of the head facing the hammer shank 36 hereinafter described is provided with a V-shaped slot 37. The hammer shank 36 carries a similar shaped wedge 38 designed to engage in the slot. The wedge and slot coact to constitute a shock absorbing device for dampening out the tendency of the hammer to vibrate in its recoil movement from the string. The inter-engaging faces of this device are defined by felt facings 39 and 40. It is important to the proper operation of this wedging device that the angularity of the wedge and its associated slot be properly designed and this will usually be attained by experimenting with the particular action under consideration. The angle must not be so small that the hammer is frozen in position following a powerful recoil but should be free to respond repeatedly to a rapidly succeeding actuation. On the contrary the angle should not be so wide as to fail to hold the hammer against a succeeding rebound towards the string. In one practical embodiment of the invention where felt was used as a facing the angle of the slot was about 9°.

The hammer includes a butt 41 also pivotally mounted on the same pivot pin 29 which mounts the carriage. It is another feature of this disclosure that there is but one pivotal connection in the entire action. This pivot is utilized not only to pivotally mount the hammer but also to pivotally mount every element necessary to actuate the same directly from the abstract.

The hammer is provided with the usual string striking head 42 and a light spring 42' tends normally to hold the hammer in engagement with the wedging device. It is a usual practice to form all parts of such hammers of wood, usually glued together so that each head must be properly located relative to its string before the shank is glued to the butt of the hammer. In the present disclosure the shank is made of a readily bendable wire. In this way it is possible to adjust the head by slightly distorting the wire shank after the action is mounted in place and without disturbing any other part of the action or its mounting.

The action herein featured may additionally be designed to actuate a damper of conventional form. In the disclosure there is illustrated a conventional form of damper 43 pivotally mounted at 44 to some fixed part of the support. The lower end of this damper is engaged by an upstanding foot 45 forming the end of the pivoted carriage adjacent the string. The foot is normally

disposed in spaced relation to the damper as shown in Figures 1 and 2 and engages the damper only during the last part of the carriage movement, just before the hammer lets fly in its striking engagement with the string. In this way it is only the final movement of the carriage as it moves into engagement with its stop 33 that is utilized to do any effective work except to throw the hammer.

In operation the elevation of the inner end of the key in its playing operation will act through the abstract to lift the same and thus swing the carriage about its pivotal connection and finally into engagement with the stop 33. During this entire movement the hammer is engaged through the head 35 which is in spaced relation to the fulcrum of the hammer and this acts as a long arm lever for throwing the hammer. This means that during the period when the carriage is moving from its normal inoperative position shown in Figure 1 into engagement with the stop, the hammer is acquiring momentum which has as a factor the mass action of all the moving parts fulcrumed on the pivot pin 29. The parts are so proportioned that the carriage engages the stop before the hammer head engages the string. The hammer is relatively light so that it has little mass action on recoil, but at the instant of striking the string is acting under the force of the kick imparted thereto by the relatively massive carriage.

The hammer rotates about its pivot pin 100 under the force of its inertia and into striking engagement with the string. It is noted that at the instant of striking the string the hammer is entirely free of its actuating mechanism. Excepting for the relatively slight energy utilized to trip the damper into its inoperative position the entire energy inherent in the key is utilized in energizing the hammer in its string striking movement. No part of this energy is utilized for the purpose of securing the hammer in its return to normal, inoperative position as is usual in conventional forms of such actions.

The hammer on its recoil from the string is damped solely by the momentum of its recoil and wedges lightly in the friction clutch independent of the actuating mechanism and with an intensity of engagement depending solely upon the energy of recoil of the hammer away from the string and in its engagement with the felt face wedging device.

On the release of tension on the key it falls away from the abstract and the abstract is free to fall by its own weight. In normal operation of the device this fall of the abstract will be assisted by the weight of the carriage bearing on the same in its recoil from the stop 33. It may even be possible that the hammer engages the actuator before the latter has fully returned to its

normal position in which case the retreating carriage assists the hammer in giving up its energy of recoil and assists in preventing a repeated stroke of the hammer against the string.

As the point of resistance to the movement of the action is confined to the single pivotal connection at 29, and to the two sliding bearings at 15 and 16, resistance to the movement of the parts in either their actuating or reversed direction has been minimized and in practical operation there is substantially no material resistance to the movement of the action. As a result the action is characterized by extreme rapidity of movement which is found to be particularly attractive in its use in player pianos where rapid sequence of operation is necessary to effect a clear, distinct, sequence of blows on any single string when playing a rapidly repeated series of notes on that string.

As the normal position of the hammer controls the distance in which the hammer must travel in order to effect its operating stroke, the adjustment of this position provides the necessary regulation and in the device disclosed this adjustment is conveniently provided by rotating the threaded portion of the abstract into or out of the body portion.

By removing the screws 27 and 28 it is possible to lift the action, including the hammer and its actuating mechanism, from the piano as a unit. There is no other connection between the action and the piano except the connection provided by the screws 27 and 28. It is possible by this construction for the piano user to be supplied with additional units which by the use of a screw-driver, can be installed in place of a damaged or worn unit. The shank of the hammer can be bent, if necessary, to insure the proper striking position of the head and in this way an action can be repaired by the user and without necessity of skilled labor. Further it is possible to replace a hammer or carriage without removing the unit simply by releasing the holding screws 28, lifting the fingers 30, which will permit the withdrawal of the carriage, or hammer, or both. Repairs can then be made to the removed parts, after which they can be readily repositioned in place all without disturbing the remaining mechanism or effecting the operation of the piano except in the removed parts.

By actuating the soft pedal the key may be partially raised to any desired extent depending on the angle through which the cam 46 is rotated and in this way the normal inoperative position of the hammer head may be adjusted while playing the instrument.

65 By means of an action of the character

described all the advantages of a quick stroke and return of the hammer characterizing old forms are retained and a much simplified structure is provided featuring economy both in manufacturing cost as well as efficiency in operation.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. A piano action including a pivoted carriage, a hammer butt pivoted to the carriage and actuated thereby, a hammer carried by said butt, a vertically movable abstract capable of moving independent of the carriage and adapted to be raised into lifting engagement with the carriage to lift the same on its hammer actuating stroke, a stop for limiting the movement of the carriage in its actuating stroke and said hammer mounted to provide a movement thereof under its own inertia beyond the position of the carriage when in engagement with the stop and into operative engagement with its associated string.

2. In a piano action, the combination of a pivotally mounted carriage, means for moving the carriage on its operative direction, a hammer pivotally mounted and adapted to be moved on its string-striking stroke by the operative movement of the said means, said hammer and carriage provided with wedge forming elements coacting to form a V-wedge for dampening out vibrations of the hammer on its rebound from the string.

3. In a piano action, the combination of a string, a pivoted hammer for said string, a power member having a limited string striking movement in one direction, means between the power member and the hammer for translating the kinetic energy in the actuating stroke of the power member into a movement of the hammer in its string striking direction and said hammer being mounted to permit the hammer to rebound idly from the string independent of the translating means and clutching means between the hammer and translating means for cushioning the rebound of the hammer.

4. In a piano action, the combination with a string, of an abstract having an actuating movement in one direction for a limited distance, a pivoted hammer, a driving connection between the abstract and hammer, said hammer having a freedom of movement independent of the connection, said connection including means for utilizing the actuati-

ing stroke of the abstract for moving the hammer in its operative stroke toward its string and the rebound of the hammer from the string constituting the means for returning the hammer independent of the abstract to its initial inoperative position and a friction clutch disposed in the path of the rebounding hammer for restraining any further rebound of the hammer.

10 5. In a piano action, the combination with a string, of a support, a carriage mounted thereon, a hammer butt carried by the carriage, a hammer carried by the butt, a single pivotal connection for both the carriage and butt, a stop for limiting the movement of the carriage on its actuating stroke while permitting the butt to continue to turn independent of the carriage and thus permit the hammer to travel on into its striking engagement with its associated string under its own inertia.

6. In a piano action, the combination of a hammer, a stop for limiting the recoil movement of the hammer, and means between the hammer and stop for securing the hammer against rebound, said means including a V-shaped wedge engaging in a similarly shaped slot, said slot disposed in the plane of movement of the hammer, the interengaging faces of both the slot and wedge being covered with felt.

7. In a piano action, the combination of a pivoted carriage, constituting part of the mechanism for actuating a hammer, a V-shaped element secured to the carriage and movable therewith, a hammer pivoted for movement concentrically of the axis of rotation of the carriage, and a wedge shaped member carried by the hammer and adapted to engage in the V-shaped element and coacting therewith to form a friction clutch for dampening out the recoil vibratory movement of the hammer and a cushioning material disposed between the operative faces of said friction clutch.

8. In a piano action, the combination of a pivoted carriage, constituting part of the mechanism for actuating a hammer, a V-shaped element secured to the carriage and movable therewith, a hammer pivoted for movement concentrically of the axis of rotation of the carriage, and a single, rigid wedge shaped member carried by the hammer and adapted to engage in the V-shaped element and coacting therewith to form a friction clutch for dampening out the recoil vibratory movement of the hammer.

9. In a piano action, the combination of a hammer, a stop for limiting the recoil movement of the hammer, and means between the hammer and stop for securing the hammer against rebound, said means including a V-shaped wedge engaging in a similarly shaped slot and said wedge and slot disposed in the plane of movement of the hammer.

10. In a piano action, the combination of a key, an abstract guided for vertical reciprocatory motion and resting on the key, the upper end of the abstract providing a hammer locating seat, a hammer actuator pivotally mounted and engaging said seat, said actuator having a hammer stop fixed rigidly thereto, a hammer pivotally mounted and normally engaging said stop on the actuator and means for varying the length of the actuator thereby to vary the position of said hammer stop.

11. A piano action including a key, an abstract mounted for vertical reciprocatory movement, resting entirely on said key and so actuated thereby, a hammer actuator pivotally mounted and including an arm normally resting on the abstract and a hammer pivotally mounted and movable relative to the actuator actuated by the actuator in its rotary movement under the lifting action of the key controlled abstract, and said hammer located in its normal inoperative position by the actuator in its engagement with the abstract and means for varying the operative length of the abstract thereby to vary the distance between the actuator and the key.

12. In a piano action, the combination of a fixed stop, a hammer operably independent of said stop, an actuator for the hammer pivotally mounted and limited by said stop in its hammer actuating movement, an abstract for swinging the actuator in its hammer operating movement and constituting a stop seat for limiting the return movement of both the actuator and the hammer and a single regulating means for varying the operative position of said seat and constituting the sole necessary means for regulating the action.

13. A piano action including a pair of vertically spaced supports provided with vertically aligned apertures constituting anti-friction guideways and a rod constituting an abstract guided in said apertures.

14. In a piano action, the combination of a pivotally mounted hammer, an abstract mounted for vertical reciprocatory movement, guiding means for confining the abstract to a straight line reciprocatory movement, and a single, one piece rigid lever constituting all of the means for translating the longitudinal movement of the abstract in its upward direction into the rotary movement of the hammer necessary to effect its string striking stroke, and a single stop disposed in the path of rotary movement of the actuator for limiting the movement of the actuator, abstract and key in their string striking movement.

15. In a player piano, the combination with a support, a set of strings and a set of abstracts mounted in operative position on the support and constituting a fixed part

of the piano construction, of a readily replaceable unit adapted to be installed in position on said support, said unit including a hammer, a hammer actuator provided with a hammer impact and rebound stopping part and a pivot pin for mounting both the actuator and hammer in position, said actuator constituting all the necessary mechanism for actuating the hammer from one of the abstracts.

16. An article of manufacture constituting a replaceable unit designed to be mounted in a piano as part of its action, said unit including a support provided with means for securing the same in place, a hammer pivoted to said support and mechanism for transferring action from an abstract forming part of the action in the piano to the hammer forming part of the replaceable unit.

17. In a piano action, the combination with a key actuated abstract and a string, of a mounting providing a pivot pin support, a pivot pin engaging said mounting, readily removable means for securing the pin in place and string striking mechanism carried by the pin and removable therewith bodily from the remaining parts of the action.

18. In a piano action, the combination with a key actuated abstract and a string, of a readily replaceable unit provided with a pivot pin seat, a pivot pin removably positioned in said seat, means for locking the pin in place and a hammer and associated actuating mechanism pivotally mounted on said removable pin.

19. In a player piano, the combination with a support, a set of strings and a set of abstracts mounted in operative position on the support and constituting a fixed part of the

piano construction, a readily replaceable unit adapted to be installed in position on said support, said unit including a hammer and all the necessary mechanism for actuating the hammer from the abstract. 45

20. In a player action, the combination of a string, a hammer therefor including a hammer butt pivotally mounted, a hammer head and a bendable wire constituting the hammer shank connecting the butt and head, 50 said wire shank constituting the means for adjusting the head to its proper striking position relative to the string.

21. In a player action, the combination of a string, a hammer therefor mounted for 55 rotary movement about a fixed axis, said hammer including a bendable part constituting the means for adjusting the head of the hammer relative to the string.

22. In a piano action, the combination of a single driving connection for translating a linear movement of an abstract into a rotary movement of a hammer, said connection being pivotally mounted and provided on one side with an abstract blow receiving face, 65 and provided with a rigid extension constituting a hammer engaging member fixed in position relative to the axis of rotation of said connection and adapted to strike the hammer. 70

23. A piano action including an abstract mounted accurately for vertical reciprocating movement, having a lower end adapted to rest on a key and having its upper end fashioned to bear on and lift a hammer actuator. 75

Signed at Newark, in the county of Essex and State of New Jersey, this twelfth day of April, A. D. 1923.

CHARLES EWEN CAMERON, JR.
